Attorneys

UNITED STATES PATENT OFFICE.

ERNEST G. HARRIS, OF NORTH VANCOUVER, BRITISH COLUMBIA, CANADA.

SPRINKLER-SYSTEM ALARM VALVE.

1,425,254.

Specification of Letters Patent. Patented Aug. 8, 1922.

Application filed May 24, 1920. Serial No. 383,897.

To all whom it may concern:

Be it known that I, ERNEST G. HARRIS, citizen of the Dominion of Canada, residing at North Vancouver, in the Province of 5 British Columbia, Canada, have invented certain new and useful Improvements in Sprinkler-System Alarm Valves, of which the following is a specification.

This invention relates to an alarm valve 10 for a sprinkler system and is designed to afford a full straightway passage for the water to the sprinkler pipes, and when there is a sufficient current of water to open the valve, it will unfailingly operate the alarm 15 but will not give a false alarm when the valve is slightly opened and closed, as when jerked off its seat by water hammer.

The invention is fully set forth in the following specification, reference being made to 20 the drawings by which it is accompanied, in which:

Fig. 1 is a vertical longitudinal section on the line 1—1 in Fig. 2.

Fig. 2, a plan of the same.

25 In these drawings 2 represents the casing which contains the valve, which casing has a flange 3 for connection to the water service and one 4 for connection to the sprinkler system of the building.

30 Adjacent the water service connection 3 a bronze valve 6 seats downward on a bronze ring 5 inserted in the casing. This valve 6 has a lug 7 projecting from one side by which the valve is pivoted loosely on a pin 8 mounted in the walls of the casing 2. The 35 end of the lug 7 adjacent the pivot bearing 8 is shaped somewhat as shown in Fig. 1, to form a projection 9 eccentric to the bearing of the pin and this projection 9 is adapt-

40 ed to engage the tail end of a short lever 10 pivotally mounted on a pin 11 in the walls of the casing parallel to the pin 8. The other end of this lever 10 carries a hemispherical valve 12 adapted to normally seat on the 45 edge of and close an aperture through a nipple 13 screwed into the casing 2.

The side of the casing 2 toward which the valve is mounted is open to afford access to the valve and its connection and is closable 50 with a cover 14. This cover has a projection 15 from its inner side, which forms a limiting stop for the valve 7, checking it when open in a position from which it will be sure to fall to its seat when a current of water 55 ceases to flow through the valve.

Across between the seat of the valve 6 and

that of the alarm valve 12 is a ridge 17 designed to prevent scale or dirt obtaining access to the seat of the valve 12 and to further protect it a gauze screen 16 is secured 60 to the cover 14 and projects inward and downward therefrom to the ridge 17.

The outwardly projecting end of the nipple 13 is connected by a pipe to the water motor of the alarm gong or to an intermediate retarding chamber, if such is considered necessary.

Provision is made at 18 and 19 for the connection of draw-off pipes below and above 70 the valve and at 20 for a gauge pipe connection.

As shown in Fig. 2, the pins 8 and 11 on which the valves 6 and 12 are pivoted are pocketed in the casing 2, and the apertures through which they are introduced are each 75 closable by a plug, and the end of each pin has a tapped hole by which the pins may be withdrawn by a handle rod having a threaded end.

It will be noticed that the projecting end 80 9 of the valve pivot connection is normally free of contact with the tail end of the lever 10, so that fluctuation in the pressure of the water main to which the casing is connected at 3, while it may lift the valve 6 slightly 85 off its seat, will not in that slight movement operate to open the valve 12, but if water is withdrawn from the sprinkler system which is connected at 4, the valve 6 will be thrown open and the eccentric projection 9 will engage the tail end of the lever 10 and will lift the valve 12 off its seat that the water under pressure will flow through the nipple 13 to operate the water motor and ring the alarm 90 gong.

This freedom from engagement of 9 with 12 also allows the valve 6 to gain a certain momentum which will overcome the resistance in opening the valve 12 and will carry the valve 6 up to the full open position.

It will be noted also that the projecting end 9 is so formed in relation to the end 105 of 10 that the first lifting engagement of 9 with 10 will be applied at such distance from the pin 11 as will afford a good lifting pressure to open the valve 12.

The valve 6 thus forms a positive means for actuating an alarm when there is a current of water from the water service to the sprinkler system, such as will open the valve 110 6, but any fluctuation of pressure in the water service pipe though it may lift the

valve 6 off its seat, will not lift it so far as to open the valve 12 and sound an alarm. These false alarms are a frequent source of trouble in existing alarm devices of this class where the alarm is actuated by movement of the valve off its seat.

Having now particularly described my invention, I hereby declare that what I claim as new and desire to be protected in by Letters Patent, is:

1. An alarm valve for a sprinkler system, comprising in combination, a hollow casing adapted for connection to a water service and to the pipe of a sprinkler system, a valve within the chamber seating outward against the water service connection, an alarm service connection between the water service connection and the sprinkler pipe connection, a valve closing the alarm service connection, means permitting opening of the water service valve to a certain extent without opening the alarm service valve, and means whereby opening of the water service valve beyond that limit will open the alarm service valve.
2. An alarm valve for a sprinkler system, comprising in combination, a hollow casing adapted for connection to a water service and in the same alignment to the pipe of a sprinkler system, a valve within the chamber seating outward against the water service connection, an alarm service connection from within the chamber adjacent the water service connection, a valve closing the alarm service connection, and means for opening the valve of the alarm service connection by means of the valve of the water service connection when the last named valve has moved a certain predetermined amount off its seat.
3. An alarm valve for a sprinkler system, comprising in combination, a hollow casing having a flanged connection to a water service and in direct alignment therewith a flanged connection to the pipe of a sprinkler system, a valve seating from within the casing on the water service connection, a relatively smaller alarm service connection from within the casing above and adjacent the water service connection, a lever pivotally

connected within the casing intermediate the water service and alarm service connection, said lever having at one end a valve closing the alarm service connection and at the other end a projection designed to be engaged by the water service valve on movement of it off its seat beyond a certain predetermined amount.

4. An alarm valve for a sprinkler system, comprising in combination, a hollow casing having a flanged connection to a water service and in direct alignment therewith a flanged connection to the pipe of a sprinkler system, a valve seating from within the casing on the water service connection, said valve being pivotally connected to the casing, a relatively smaller alarm service connection from within the casing above and adjacent the water service connection, a lever pivotally connected within the casing intermediate the water service and alarm service connection, said lever having at one end a valve closing the alarm service connection and at the other end a projection designed to be engaged by the pin-connected portion of the water service valve after that valve has been opened a limited amount.

5. An alarm valve for a sprinkler system, comprising in combination, a hollow casing having a flanged connection to a water service and in direct alignment therewith a flanged connection to the pipe of a sprinkler system, a valve seating from within the casing on the water service connection, a relatively smaller alarm service connection from within the casing, above and adjacent the water service connection, a lever pivotally connected within the casing intermediate the water service and alarm service connection, said lever having at one end a valve closing the alarm service connection and at the other end a projection designed to be engaged by the water service valve on movement of it off its seat beyond a certain predetermined amount, and a gauze screen protecting the alarm valve seat.

In testimony whereof I affix my signature.

ERNEST G. HARRIS.
